METHOD OF CRYSTALLIZING MATERIAL

John Henry Thompson, Burlingame, and Edward Taber Winslow, Saratoga, Calif., assignors to J. D. & A. B. Spreckels Company, San Francisco, Calif., a corporation of California

Application October 4, 1940, Serial No. 359,664

12 Claims. (Cl. 127—58)

Our invention relates to the crystallization of material from solution; and more particularly to the crystallization of sugar.

It is among the objects of our invention to provide a method for effecting continuous crystallization.

Another object is to provide means for maintaining crystallization of the material at substantially its maximum rate.

Another object is to provide a method which gives positive control of the various factors affecting crystallization, whereby crystals may be grown in accordance with a predetermined schedule.

The invention possesses other objects and features of advantage, some of which, with the foregoing, will be set forth in the following description of our invention. It is to be understood that we do not limit ourselves to this disclosure of species of our invention, as we may adopt variant embodiments thereof within the scope of the claims.

Referring to the drawing, the figure of the drawing is a side view, partly in section and partly in elevation, showing apparatus illustrating the method of our invention.

While the method of our invention is adaptable for recovering any crystallizable material from solution, it was developed particularly in connection with the manufacture of sugar. Continuous crystallization processes have been used in making salt, such as sodium chloride, but in the past have not successfully been applied to making sugar, principally because sucrose has a low rate of crystallization relative to inorganic salts.

Heretofore the sugar industry has largely depended upon using a vacuum pan in which evaporation of syrup and crystallization of the sugar occurs simultaneously. This is strictly a batch or discontinuous process; the capacity of the pan being the limiting factor, and its proper functioning depending upon the skill of the operator or "pan boiler" who by inspection and sampling determines when "the strike" has been made and the pan is to be emptied.

In attacking the problem of continuous crystallization of sucrose it became apparent to us that the conditions imposed by the vacuum pan were incompatible with either continuous operation or positive control, and that a new approach would have to be made. Thus, we appreciated the need for divorcing the concepts of evaporation per se and crystallization; that is, separating the step of evaporation (purely for the purpose

of concentrating the syrup) from the subsequent step of crystallization. By separating these steps, positive control of crystallization is possible.

5 We also recognized that when syrup is concentrated beyond saturation it first enters a meta-stable state of supersaturation in which crystals grow but are not newly formed, and subsequently passes into a labile state in which new crystals 10 are spontaneously formed. Since spontaneous formation of crystals is erratic, it became apparent to us that positive control would require inoculation with preformed seed crystals of known characteristics. Such crystals can then 15 be grown to desired size in a supersaturated solution maintained in the meta-stable state.

We also recognized that the rate of crystal growth depended upon the degree of supersaturation, purity of solution, surface area of growing crystals presented to the solution, and distribution of the crystals in the solution. With these factors under control, crystallization may 20 be carried out at the maximum rate.

Our improved method was developed with due 25 regard to these factors, and provides a system for the continuous production of sugar under controlled conditions so that the crystals grow in accordance with a predetermined schedule.

In terms of broad inclusion, our method of 30 crystallizing material from solution comprises maintaining a body of the solution under conditions favorable for crystal growth, continuously growing crystals in the body, and continuously discharging finished crystals from the body. The 35 crystals are preferably grown from preformed seed crystals of predetermined number and size introduced into a lower zone in the body, and the growth of the crystals is preferably regulated by introducing controlled quantities of fresh solution 40 of predetermined concentration and temperature into overlying zones of the body, and by maintaining the body under a predetermined absolute pressure. By this arrangement the solution in the crystallizing body may be maintained 45 at a substantially constant predetermined supersaturation, calculated to give maximum crystal growth; and the boiling which takes place at the reduced pressure serves to agitate the mass for dispersing the crystals to present a maximum 50 crystal surface to the solution for optimum growth.

Still speaking in broad terms, our method is 55 illustrated by apparatus which includes a crystallizer unit designed to retain the solution in different zones increasing in size from bottom to

top of the unit. Separate means are provided for evaporating solution to a predetermined concentration and temperature and for introducing this fresh solution into the several zones in the crystallizer. Means are also provided for treating a portion of the concentrated solution to produce seed crystals and for introducing the same into a lower zone. Means are further provided for evacuating the crystallizer to establish a predetermined temperature gradient in the body of solution; and a barometric duct is arranged to discharge finished crystals from an upper zone.

In greater detail, and referring to the drawing, our preferred apparatus for carrying out the method of crystallizing sugar comprises a suitable evaporator 2 fed by a syrup line 3. In a sugar refining plant this evaporating unit replaces the vacuum pan, it being understood that preceding stages of evaporation are carried out in the ordinary manner. The syrup is heated in evaporator 2, as by a steam coil 4, and is boiled under vacuum maintained through suction line 5. Evaporation is preferably controlled by suitable devices to continuously concentrate the syrup to some constant concentration, preferably not over the saturation point, at a predetermined temperature. Since unit 2 functions simply as an evaporator its operation may be made wholly automatic by a suitable motorized valve in line 3 responsive to boiling point rise in the evaporator to maintain a constant concentration. This type of evaporator regulation is a proved control under such conditions.

From the evaporator the concentrated solution is recirculated through a closed circuit or duct 6 by a suitable pump 7. A valve 8 is preferably provided for pressure control in the circuit. Since the syrup at this stage of the process is not concentrated above saturation it may be readily handled without danger of crystallization; and the recirculation system provides a constant supply of hot, concentrated, crystal-free syrup for the next stage of our process.

A crystallizer 9 is provided for holding a body of syrup. This unit preferably comprises a plurality of say three cylindrical sections having conical lower portions to divide the contained solution into a series of zones 11, 12 and 13; the sections increasing in diameter and size from bottom to top of the unit. While three zones are shown, it is understood that more may be provided. If desired the crystallizer unit may be in the form of a simple cone, but the sectional construction is preferred to provide more distinct zoning of the solution.

Means are provided for introducing preformed seed crystals into lower zone 11 of the crystallizer. For this purpose a duct 14 controlled by a valve or orifice 17 is connected with circuit 6 and a heat exchanger or cooler 18, preferably formed by a water jacket around the duct, is provided in this line to supersaturate the solution. The solution at this point is supersaturated to the labile state, say a supersaturation above 1.6, where crystals may be shocked out of the solution by agitation. Duct 14 is connected with a seeder unit comprising a housing having a cold water jacket 21, and containing a shaft 22 rotated by a pulley 23. A multiplicity of radial arms or spikes 24 function to violently agitate the solution flowing through the unit. This agitation serves to shock minute seed crystals out of the supersaturated solution.

The number and size of the seed crystals shocked out depends upon the degree of super-

saturation, rate of agitation and quantity of solution being treated. These factors are controlled by the amount of cooling, speed of the agitator, and rate of solution flow, all for the purpose of

5 supplying the crystallizer with a predetermined number of seed crystals of given size. The seed growth is further controlled by introducing controlled amounts of fresh concentrated solution into end 26 of the seeder through line 27 having 10 a valve or orifice 28. Means are also provided for destroying the supersaturation of the solution surrounding the seed. For this purpose the end portion 26 of the seeder is unjacketed so that the temperature of the solution may rise. If desired a thin syrup may be added to the crystal bearing solution to assist in destroying supersaturation of the mother liquor. By thus destroying the supersaturation the formation of 15 seed is definitely stopped at a given point. The 20 seed-bearing solution is discharged downwardly into lower zone 11 of the crystallizer through a duct 29.

The seed-bearing solution flowing into the crystallizer thus affords a continuous supply of seed 25 crystals for inoculating the syrup in the lower zone of the crystallizing body. This treatment of a portion of the syrup to produce the seed crystals is an important feature of our invention because it not only provides a convenient and 30 continuous supply of seed, but also provides a control for the size and number of seed introduced into the crystallizer.

Means are also provided for continuously introducing fresh concentrated syrup from circuit 6 35 into the crystallizer. For this purpose a duct or line 30 controlled by a valve or orifice 31 leads from circuit 6 to the bottom of the crystallizer; and other lines 32 and 33 controlled by valves or orifices 34 and 35 lead from the circuit to the 40 upper sections of the crystallizer. The latter lines have suitable heads 36 and 37 for uniformly distributing the fresh solution throughout zones 12 and 13; the heads preferably having a bottom plate with a slight clearance at the periphery to 45 effect radial discharge.

Means are provided for maintaining the solution in the crystallizer in a predetermined state of supersaturation, preferably a supersaturation of about 1.2 in the meta-stable range. This may 50 be accomplished by cooling the concentrated solution by suitable means, but we prefer to effect it by evaporation. The hot solution is caused to boil at reduced pressure produced by evacuating the crystallizer through exhaust duct 38.

55 Supersaturation is also affected by the quantity, concentration and temperature of the incoming fresh solution, these factors also being under control at evaporator 2 and by the flow regulating orifices in the various ducts. After the flows and 60 temperatures become constant the supersaturation also becomes constant.

Means are further provided for agitating the solution in the crystallizer to disperse the crystals 65 throughout the several zones and thus present a maximum crystal surface to the solution for optimum crystal growth. This could be accomplished by a mechanical stirrer, but in order to avoid moving parts, we prefer to utilize the agitation caused by boiling. This agitation, accompanying the formation of steam bubbles in the solution, 70 operates to effectively distribute the growing crystals uniformly throughout the solution and prevents twinning of the crystals.

Means are also provided for continuously discharging finished crystals from the crystallizer.

To this end a barometric duct 39 leads from the upper section of the crystallizer and extends downwardly into a tank 41 which forms a liquid seal for the lower end of the duct. By this arrangement a continuous flow of crystal bearing solution may be discharged from the upper zone without breaking the vacuum in the crystallizer. Solution in tank 41 overflows into a suitable mixer 42 and thence is discharged into a centrifugal 43 for purging the crystals from solution. A series of centrifugals are preferably provided for taking care of the continuous flow from the crystallizer.

Operation.—In starting the apparatus the seed bearing solution is introduced into lower zone 11 through duct 29 together with fresh concentrated solution through duct 30. Barometric duct 39 is sealed by liquid or some mechanical means to permit initial evacuation of the unit, and vacuum is drawn in the crystallizer. Under reduced pressure the hot liquor boils to supersaturate the solution and agitate the mass to disperse the crystals. Under these controlled conditions the seed crystals grow in accordance with a predetermined schedule. At some point the rate of growth diminishes with respect to supersaturation, and is compensated for by the introduction of fresh solution in the upper zones through ducts 32 and 33. The crystals starting from seed are thus allowed to grow in the different zones of solution as the crystals flow upwardly through the body. Viewed in another way, the partially grown crystals in one zone provide nuclei for crystal growth in an overlying zone; in other words, one zone provides a fractional seeder for another zone. Finally the solution level reaches the upper portions of the crystallizer and discharges through duct 39.

When temperatures and flows become constant the crystallizer runs steadily, taking in seed and fresh solution continuously and discharging finished crystals at a continuous rate through duct 39. In order to stop the apparatus, the seeder is stopped and solution flow is continued until all crystals in the unit are displaced.

During operation there are several important features to be noted in our system. It has already been mentioned that crystals grow without formation of new seed if the solution is maintained in the meta-stable state. In order to effect maximum growth rate of the crystals, the solution is preferably maintained at the upper limit of the meta-stable state. As the crystals grow their capacity for robbing the solution of sugar increases, which would tend to decrease the supersaturation in the upper zones. This is compensated for by introducing the fresh concentrated solution in controlled quantities into the upper zones, and also by maintaining the temperature in the crystallizing body along a predetermined gradient. The temperature decreases along a gradient in accordance with the laws of hydrostatic pressure, and the desired gradient is established by the degree of vacuum maintained in the unit. Since supersaturation is a function of concentration and temperature, both of which are under control, the supersaturation may thus be maintained substantially constant for optimum rate of crystal growth.

In order to maintain crystal growth at its highest rate it is also desirable to present a maximum surface area of the growing crystals to the solution. This requires uniform distribution of the crystals throughout the solution; and as the crystals become larger a wider dissemination of the crystals throughout larger volumes

of the solution is desirable. The gentle boiling that takes place in our unit effects uniform distribution of the crystals in any given zone. Since the zones increase in size toward the top, the upper zones offer a greater volume of fluid in which the crystals may be dispersed. The agitation in the several zones is a function of the cross-sectional area, and is cumulative as the fluid height increases, thus insuring proper size distribution of the crystals.

Another feature of our crystallizer is that the plurality of zones tends to produce finished crystals of substantially uniform size. A single section crystallizer may be considered to give a size distribution of from initial seed size to final grain size, while an infinite number of sections would produce crystals of identical size. Within practical limits however, a three section crystallizer provides sufficient uniformity in the grain.

Still another feature is that the final grain size may be varied by increasing the number of sections in the crystallizer. Furthermore, sugars of different grain size may be produced all at the same time by tapping different sections of the unit, the smaller grain sugars being drawn off from lower zones.

Example.—In apparatus having a discharge capacity of 238 pounds per minute, the three-section crystallizer 9 is designed to hold about 10,008 pounds of material; 1533 pounds being retained in lower zone 11, 5725 pounds in intermediate zone 12, and 12,750 pounds in upper zone 13. In such a crystallizer the height of the discharge opening above the bottom of the unit is about seven feet, and discharge duct 39 has a length of about twenty feet. Syrup is continuously concentrated in evaporator 2 to about 83° Brix at 101° C., and pumped through circuit 6 at the rate of about 305 pounds per minute. This saturated solution is continuously introduced into the crystallizer through ducts 30, 32 and 33 at the rate of 29 pounds per minute into zone 11, 83 pounds per minute into zone 12, and 145 pounds per minute into zone 13.

The seeder is designed to discharge seed bearing solution into the lower zone of the crystallizer through duct 29 at the rate of about 3 pounds per minute, of which 1.2 pounds comprises seed crystals having a size of about 100 microns. To accomplish this the portion of the solution flowing through duct 14 is cooled sufficiently to effect a supersaturation above say 1.6, and the seeder is operated at a speed sufficient to shock out seeds of a size and in the quantities above mentioned.

A vacuum of about 26 inches Hg is maintained in the crystallizer, causing the solution to boil with a total evaporation rate of 22 pounds per minute; of which 2 pounds is evaporated from zone 11, 6 pounds from zone 12, and 14 pounds from zone 13. When the flows and temperatures become constant under these conditions the rate of flow between zones 11 and 12 is about 30 pounds per minute, carrying 14 pounds of sugar crystals having a size of about 233 microns. At this point the mother liquor has a concentration of about 81° Brix at 78° C. The rate of flow between zones 12 and 13 is about 107 pounds per minute, carrying 57 pounds of crystals having a size of about 367 microns. At this point the mother liquor has a concentration of about 78° Brix at 68° C. The rate of discharge from zone 13 is about 238 pounds per minute, carry-

ing 143 pounds of finished crystals having a size of about 500 microns. The mother liquor at this point has a concentration of about 75° Brix at a temperature of 59° C.

It will be observed that the temperature falls along a gradient, with a temperature drop of about 10° C. per zone. Under these conditions, and with concentrated solution flowing in at the rates indicated, the supersaturation is maintained constant at about 1.2 throughout the entire body.

We claim:

1. The method of crystallizing material from solution, which comprises arranging the solution in a plurality of vertically disposed zones, introducing fresh solution of predetermined concentration and temperature into each of said zones, in sufficient quantity to maintain a substantially constant degree of supersaturation introducing seed crystals into a lower zone, maintaining a predetermined absolute pressure on the solution, and discharging finished crystals from an upper zone.

2. The method of crystallizing material from solution, which comprises passing crystals upwardly through a body of solution, and controlling concentration and temperature at different levels in the body of solution to maintain a substantially constant supersaturation throughout the solution by introducing regulated amounts of solution of controlled character.

3. The method of crystallizing material from solution, which comprises providing solution in vertically disposed zones increasing in size toward the top, introducing regulated quantities of fresh solution into said zones, introducing seed crystals into a lower zone, and discharging finished crystals from an upper zone.

4. The method of crystallizing material from solution, which comprises providing solution in vertically disposed zones increasing in size toward the top, introducing fresh solution into said zones in quantities increasing with the size of the zone, introducing seed crystals into a lower zone, and discharging finished crystals from an upper zone.

5. The method of crystallizing material from solution, which comprises introducing regulated quantities of fresh solution of predetermined concentration into vertically disposed zones of the solution, introducing seed crystals into a lower zone, boiling the solution to supersaturate it and disperse the crystals, and discharging finished crystals from an upper zone.

6. The method of crystallizing material from solution which comprises introducing regulated quantities of fresh solution of predetermined temperature and concentration into vertically disposed zones of the solution, introducing seed crystals of predetermined size into a lower zone, maintaining a predetermined absolute pressure on the solution, and discharging finished crystals from an upper zone.

7. The method of crystallizing material from a supersaturated body of solution which comprises introducing seed crystals into the lower portion of the body, agitating the body to effect dispersal of the crystals therein, continuously introducing regulated quantities of fresh solution into the body at different levels to feed the growth of the crystals, and removing finished crystals from the upper level of the body.

8. The method of crystallizing material from solution which comprises maintaining a body of the solution in a plurality of vertically disposed zones increasing in size toward the top, introducing seed crystals into the lower zone, agitating the body to effect dispersal of the crystals therein, introducing regulated quantities of fresh solution into each zone to feed the growth of the crystals, and removing finished crystals from the upper level of the body.

9. The method of crystallizing material from a body of solution which comprises introducing seed crystals into the lower part of the body and causing them to move upwardly through the body to the top thereof, and introducing into the body at different levels fresh solution of predetermined volume, temperature and concentration.

10. The method of crystallizing material from a supersaturated body of solution which comprises introducing seed crystals into the lower part of the body and causing them to move through the body to the top thereof, introducing fresh solution of predetermined concentration into the body at different levels in quantities such as to maintain substantially uniform supersaturation of the solution throughout the body, maintaining a predetermined absolute pressure upon the body, and discharging finished crystals from the top of the body.

11. The method of crystallizing material from a supersaturated body of solution which comprises introducing seed crystals into the lower part of the body and causing them to move through the body to the top thereof, continuously introducing fresh solution of predetermined volume, temperature and concentration into the body at different levels for maintaining substantially uniform supersaturation, maintaining a predetermined absolute pressure upon the body, and continuously discharging finished crystals from the top of the body.

12. The method of crystallizing material from solution which comprises maintaining the solution in a plurality of vertically disposed zones increasing in size toward the top, continuously introducing into the lower part of each zone fresh solution of controlled character and amount, agitating the body of solution, and continuously discharging the finished crystals from the upper zone.
